US00D853781S

(12) **United States Design Patent** (10) Patent No.: **US D853,781 S**
(45) Date of Patent: **** Jul. 16, 2019**

(54) **PART OF FOOD INDUSTRY MACHINE**

(71) Applicant: **NORDISCHER MASCHINENBAU RUD. BAADER GMBH + CO. KG**,
Lübeck (DE)

(72) Inventor: **Mirko Pagels**, Lübeck (DE)

(73) Assignee: **NORDISCHER MASCHINENBAU RUD. BAADER GMBH + CO. KG**,
Luebeck (DE)

(**) Term: **15 Years**

(21) Appl. No.: **35/504,772**

(22) Filed: **Mar. 22, 2018**

(80) **Hague Agreement Data**

Int. Filing Date: **Mar. 22, 2018**

Int. Reg. No.: **DM/100545**

Int. Reg. Date: **Mar. 22, 2018**

Int. Reg. Pub. Date: **Apr. 20, 2018**

(30) **Foreign Application Priority Data**

Sep. 26, 2017 (EM) 004372365-0002

(51) **LOC (11) Cl.** **31-00**

(52) **U.S. Cl.**

USPC **D7/381**; D8/20

(58) **Field of Classification Search**
